UNITED STATES PATENT OFFICE.

SAMUEL S. ROSE, OF SANTA CLARA, CALIFORNIA, ASSIGNOR TO ROSE MANUFACTURING COMPANY, OF SAN JOSE, CALIFORNIA, A CORPORATION OF ARIZONA TERRITORY.

GEARING.

No. 876,018.

Specification of Letters Patent.

Patented Jan. 7, 1908.

Application filed August 17, 1906. Serial No. 330,986.

To all whom it may concern:

Be it known that I, SAMUEL S. ROSE, a citizen of the United States, residing at Santa Clara, county of Santa Clara, State of California, have invented new and useful Improvements in Gearing, of which the following is a specification.

My invention relates to improvements in gearing.

10 The object of my invention is to provide improved gearing, whereby a shaft may be readily caused to revolve in either direction and without any tendency in the mechanism to bind during its operation.

15 My invention consists in the novel arrangement and combination of parts described in the following specification and shown in the accompanying drawing, and as claimed in the appended claims, and I declare that my 20 invention as set forth in this specification and illustrated in said drawing is so described that any person skilled in the art to which it pertains may make and use the same.

25 Referring to the accompanying drawings: Figure 1 is a plan view of my said device; Fig. 2 is a sectional view of the same; Fig. 3 is a section of said device on line $y-y$ of Fig. 2, and Fig. 4 is a section of the same on line 30 $x-x$ of said Fig. 2. Fig. 5 shows four parts that form the collar 12, each section of said collar as shown being composed of two parts, having lugs 28 containing apertures by means of which the parts are connected by 35 bolts and nuts. Fig. 6 shows the parts last mentioned as assembled upon sleeve 20 excepting one part out of contact with the other parts. Fig. 7 is a sectional view of the 40 said four parts forming the two sections of the collar 12 as joined upon the sleeve 20.

The following is a description of the parts of my device as shown in said drawing and its mode of operation.

A represents a driving shaft having a pinion 2 operating two oppositely positioned gears 3 and 4. Said gears are loosely mounted on shaft 5 between collars 6 and 7 secured to said shaft. The shaft 5 is driven in either direction by operating a lever 8 which is fulcrumed at 9 and at the upper end of said lever a pin 10 engages a groove 11 in collar 12, and at its other end said lever is connected to controlling lever 13, by the lateral movement of which lever 8 is moved.

55 The arms 14 are pivoted to collar 12 at

point 15 and at 16 to frictional shoes 17. The said shoes are fulcrumed at 18 to arms 19 which are integral with sleeve 20. When said collar 12 is caused to operate in one direction the friction from shoes 17 as operating against the circular interior of gear 4 causes said gear to revolve and, the sleeve 20 being keyed to shaft 5 thereby causes said shaft to turn in the same direction as said gear. The arms 21 are similarly pivoted to 60 collar 12 by pintle 22, and by pintle 23 to frictional shoes 24. The said shoes 24 are fulcrumed at 25 to arms 26 which are likewise integral with sleeve 20. When the collar 12 is caused to operate in the direction 70 opposite to that hereinbefore mentioned the friction from shoes 24 as operating against the circular interior of said gear 3 causes said gear to revolve, and the sleeve 20 being keyed to shaft 5, as hereinbefore set forth, 75 thereby causes such shaft to turn in the direction opposite to that turned by gear 4.

The collar 12 consists of two sections so as to allow either section to move a small distance to prevent binding, when either of the 80 frictional shoes swing on an arc caused by the pivoting of the same as shown at points 18 and 25. Each section can revolve independently of the other by the annular flange of one section turning in the groove of the other 85 section, as shown at point 27, such turning being accomplished without liability to bind.

I have described the lever 8 as shown in Fig. 1, but said lever has its upper part U-shaped, the part opposite to that shown in 90 said figure being identical with the part so shown, including the pin.

It is to be understood that while I have illustrated and described the preferred embodiment of my invention, I reserve the 95 right to make all changes which properly fall within its spirit and scope.

Having thus described my invention what I claim as new and desire to secure by Letters Patent, is:

1. Gearing, comprising a pair of loosely mounted gears, a driving shaft, a pinion thereon meshing with said gears, pivotally mounted shoes for bearing against the circular interior of said gears, a shaft for said 105 gears, a collar having two sections mounted between said gears, one of said sections having an annular flange turnable in an end groove in the other section and said collar having a central annular groove, a lever and 110

pins for shifting said collar and means for securing said shoes to said shaft, substantially as described.

2. Gearing, comprising a pair of loosely mounted gears, a driving shaft, a pinion thereon meshing with said gears, pivotally mounted shoes for bearing against the circular interior of said gears, a shaft for said gears, a collar having two sections mounted between said gears, one of said sections having an annular flange turnable in an end groove in the other section and said collar having a central annular groove, a lever and pins for shifting said collar, a horizontal lever 10 for controlling the last named lever and means for securing said shoes to said shaft, substantially as described.

3. Gearing, comprising a pair of loosely mounted gears, a driving shaft, a pinion 20 thereon meshing with said gears, pivotally mounted shoes for bearing against the circular interior of said gears, a shaft for said gears, a collar having two sections mounted between said gears, one of said sections having an annular flange turnable in an end groove in the other section and said collar having a central annular groove and sleeves 25 surrounding said shaft having arms for pivotally sustaining said shoes, substantially as 30 described.

4. Gearing, comprising a pair of loosely mounted gears, a driving shaft, a pinion thereon meshing with said gears, pivotally mounted shoes for bearing against the circular interior of said gears, a shaft for said 35 gears, a collar having two sections mounted between said gears, one of said sections having an annular flange turnable in an end groove in the other section and said collar having a central annular groove, and flanges 40 forming the walls of said groove a lever and pins for shifting said collar and means for securing said shoes to said shaft, substantially as described.

5. Gearing, comprising in combination two 45 oppositely positioned gears, a collar consisting of two sections, each of said sections being arranged to endwise engage the other section, and a shoe pivotally connected to each of said sections so as to bear against the 50 interior of one of said gears upon the lateral movement of said collar in the direction of said gear.

In testimony whereof I affix my signature in presence of two witnesses.

SAMUEL S. ROSE.
